UNITED STATES PATENT OFFICE.

RAYMOND H. SMICKLE, OF BELVIDERE, NEW JERSEY.

PAPER FASTENER.

Application filed April 4, 1927. Serial No. 180,919.

This invention relates to paper fasteners, but more particularly to a double ended paper fastener in which the tongue like ends of the members comprising the fastener are capable of being bent flatly against opposite sides of papers or the like, and are capable of remaining in bent position by virtue of their own stiffness.

The invention comprises, briefly, a pair of tongue like members, attached together intermediate their ends. The means which serve to hold the members together may be formed integrally therewith or, may consist of a separate piece arranged about or through the members in a manner to prevent relative longitudinal movement thereof as well as to prevent separation of the members at a point at which they are secured.

One object of the invention is to enable the addition and removal of sheets from either side of a stack of papers, or the like, without necessitating the removal of the fastener which holds them together.

Another object is to enable separately fastened piles of papers to be laid on top of each other so that the ends of the paper will lie at approximately the same level.

Other objects will be in part obvious and in part pointed out hereinafter.

The invention consists of the combination and arrangements of parts substantially as hereinafter described and more particularly pointed out in the appended claims and illustrated in the accompanying drawings, in which

Figure 1 is a view in elevation of the fastener,

Figure 2 is a side view in elevation of the fastener shown in Figure 1,

Figure 3 is a view in elevation illustrating the manner in which the members comprising the fastener may be formed,

Figure 4 is a view in section taken through Figure 2 on the line 4—4 looking in the direction of the arrows,

Figure 5 is a view similar to Figure 1 showing a modification of the invention,

Figure 6 is a detail elevation of one of the members of the fastener disclosed in Figure 5,

Figure 7 is a view similar to Figure 6 illustrating the other member of the fastener shown in Figure 5,

Figure 8 is a transverse section taken

through Figure 5 on the line 8—8 looking in the direction of the arrows,

Figure 9 is a perspective view in elevation illustrating a modified form of fastener,

Figure 10 is an elevation of the members comprising the fastener shown in Figure 9,

Figure 11 is an elevation of another modified form of the invention,

Figure 12 is a side view in elevation of the form of fastener shown in Figure 11,

Figure 13 is a view in section taken through Figure 11 on the line 13—13 looking in the direction of the arrows, and

Figure 14 is an elevation illustrating the manner in which the fastener may be applied for holding sheets of paper together.

Referring to the drawings, and at first more particularly to the modification disclosed in Figures 1 to 4 inclusive, the invention comprises a pair of flexible tongue like members A and B connected at adjacent sides by a strip C which forms an integral part of the members A and B and is preferably located approximately midway between the ends of the members. The strip C in this instance is bent to permit the members A and B to lie face to face to each other in the manner illustrated in Figures 2 and 4.

The members A and B are preferably staggered somewhat so that one end of one of the members protrudes slightly beyond the corresponding end of the other member. In this way the members may be conveniently separated to bend them about the material they are intended to secure together.

Suitable means is provided for preventing unbending of the strip C and thus also to hold the members securely together. To that end a projection or clip D is formed integrally in this instance with the member B to engage a slot A' in the member A. The clip D is preferably of a length to enable it to be bent over the outer surface of the member A. The projection D may be of substantially the same width as the strip C and may also lie in the same transverse plane as the said strip.

The modified form of fastener illustrated in Figures 5 to 8 inclusive comprises two members E and F. These members are formed separately and, as in the preferred modification, are staggered slightly for the purpose hereinbefore described. In this instance the members are secured together by

means of lateral clips G formed integrally with the member E and bent to engage slots H in the sides of the member F. The clips G are preferably of sufficient length to enable them to slightly overlap the outer surface of the member F.

In the modification disclosed in Figures 9 and 10, a pair of symmetrical members J are shown having apertures K intermediate their ends. The apertures K are preferably formed midway between the edges of the members, although, if desired, these apertures may be located between the longitudinal center and one of the edges, depending upon the width of the material from which the members are formed.

In order to hold the members J securely together a wire or pin J' is inserted in the apertures K and is bent to engage grooves L formed in adjacent edges of the members. The grooves L may be semi-circular as illustrated or may be of a depth equal to the thickness or diameter of the pin J', thus permitting the pin to lie flush with the edge of the members.

In the form of fastener disclosed in Figures 11 to 13 inclusive, a pair of members F, shown in detail in Figure 7, are arranged parallel to each other so that the slots H of the several members lie in the same transverse plane. The members F in this instance are held securely together by a clip O, which clip may be of the same material as the member F and is preferably of substantially the same width as the slots H wherewith it cooperates to hold the members against relative longitudinal movement. In this instance the clip O is of sufficient length to permit the ends thereof to be bent as at P to engage the outer surface of one of the members F for clamping the members F securely together.

Although the slots H are shown as being of less depth than the thickness of the clip O, it is to be understood, however, that the depth of the slots H may equal the thickness of the clip. In such case, of course, the outer surfaces of the portions of the clip adjacent the slots will lie flush with the edges of the members F.

The manner in which the foregoing described fastener may be applied to a stack Q of sheets of paper, or the like, is illustrated in detail in Figure 14. In this showing the sheets are so arranged that the perforations of the several sheets coincide. The fastener may then be inserted in the perforations and the ends of the members comprising the fastener may be bent outwardly against the outer surfaces of the outer sheets.

By means of the foregoing described invention, sheets of paper may be removed from either side of a stack or pile of papers without necessitating the removal of the fastener as is the case in the usual type of

fastener, in which heads or buttons act as stops to abut one side of the papers. In the usual type of fastener, sheets can be removed only from one side of the stack without removing the fastener. To remove sheets from the other side of the stack requires the removal of the fastening device. In consequence, the papers frequently become shifted about so that the perforations of the several sheets are drawn out of alignment with respect to each other, thus causing considerable difficulty and waste of time to again arrange the papers in such manner that the fastener may be inserted into the perforations. Also, the heads or buttons formed on such fasteners are rather bulky so that when a number of separately secured stacks of papers are laid on top of each other, one end of the pile thus formed is considerably higher than the opposite end. This, of course, acts as a limitation to the number of separately secured stacks of paper which may be piled on top of one another.

The present invention aims to overcome these objectionable features and, due to the manner in which the ends of the tongue-like members may be flattened against the side of the papers and to the comparatively small cross section of the members, the ends of the papers will lie at practically the same level.

In the drawings the proportions of the several members have been somewhat exaggerated for convenience of illustration. It is to be understood, however, that the various elements comprising the fasteners may be suitably proportioned to meet immediate requirements.

I do not wish to limit the invention to the precise showing in the drawings, and it is to be understood that the invention may be further modified without departing from the spirit of the invention or the scope of the claims.

I claim:

1. A paper fastener comprising a pair of pliable double ended members arranged in parallel relation, one of said members having a slot, and means in engagement with said slot for holding the members together intermediate their ends.

2. A paper fastener comprising a pair of pliable members of substantially uniform width throughout their length and arranged in face to face relation, one of said members having a slot, and means engaged by said slot for clamping the members together.

3. A paper fastener comprising a pair of pliable double ended members, one of said members having a slot, and a clip on the other member engaged by the slot and bent around the first said member to clamp the members together intermediate their ends.

4. A paper fastener comprising a pair of pliable double ended members, a strip con-

necting adjacent edges of the members, one of said members having a slot in one edge, and a clip on the other member bent into engagement with the slot for clamping said members together.

5. A paper fastener comprising a pair of pliable double ended members disposed in face to face relation and arranged in staggered formation to enable the end of one member to extend beyond the adjacent end **10** of the other member, one of said members having a slot, and a clip on the other member engaging the slot to clamp the members together.

In testimony whereof I have signed this **15** specification.

RAYMOND H. SMICKLE.
